FLUID COOLING SYSTEM

Harry R. Crago, Verona, N. J., assignor to General Electric Company, a corporation of New York

Application December 23, 1937, Serial No. 181,274

11 Claims. (Cl. 62—4)

My invention relates to fluid cooling systems and particularly to such systems employing a plurality of refrigerating machines.

Fluid cooling systems are frequently required to operate under widely different conditions of load. Refrigerating machines operate most efficiency at loads within a fairly narrow range and it, therefore, becomes desirable in some systems to utilize a plurality of refrigerating machines so that only the number of machines necessary to carry the load need be connected to operate. In such systems, each machine may be operated more nearly within its most efficient range of load. Accordingly, it is an object of my invention to provide a fluid cooling system having a plurality of refrigerating machines and including an improved arrangement for controlling the sequence of operation of the refrigerating machines.

Another object of my invention is to provide a fluid cooling system having a plurality of refrigerating machines and an improved arrangement for selecting the machines for operation in accordance with the load on the system.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawings in which Fig. 1 is a diagrammatic illustration of an air cooling system including a refrigerating machine having two condensing units and embodying my invention; Fig. 2 is a diagrammatic illustration of an air cooling system utilizing two refrigerating machines embodying my invention; and Fig. 3 is a diagrammatic illustration of a modified arrangement of an air cooling system similar to that shown in Fig. 2.

Referring now to the drawings, in Fig. 1 I have shown an air cooling system including a duct 10 having a fresh air inlet 11 and a return air inlet 12 provided with filters 13 and 14 respectively. The fresh and re-circulated air enter the duct and are circulated therethrough by operation of a fan 15 driven by a motor 16, the mixture of air being discharged into the room or other enclosure to be conditioned through an outlet 17. In order to cool the air passing through the duct 10, I provide a refrigerating machine including evaporators 18 and 19 arranged in the duct 10 and connected in a closed refrigerant circuit including condensing units 20 and 21 con-

nected in parallel to supply liquid refrigerant to the evaporators 18 and 19 through a liquid line 22 and to withdraw gaseous refrigerant from the evaporators through a suction line 23. The condensing unit 20 includes a compressor 24, a condenser 25, and a liquid receiver 26. The condenser 25 is cooled by water circulated through a casing 27 surrounding the condenser and having a cooling water inlet and an outlet as indicated by the arrows. The condensing unit 21 10 comprises a compressor 28, a condenser 29, a liquid receiver 30 and a water circulating casing 31 having a cooling water inlet and an outlet as indicated by the arrows. The compressors 24 and 28 are driven by motors 32 and 34 respectively. A thermostat 35 arranged in the enclosure to be conditioned is provided to control the operation of the cooling system. When there is a demand for cooling, one or both of the motors 32 and 34 are operated to compress refrigerant 20 and discharge the compressed refrigerant into the corresponding one of the condensers 25 and 29 where the refrigerant is cooled and liquefied by the circulation of water thereover, the liquid refrigerant being collected in the receivers 26 and 30. Liquid refrigerant flows through the liquid line 22 and is admitted to the evaporators 18 and 19 by operation of thermostatic expansion valves 36 and 37 having thermostatic elements 38 and 39 respectively connected to the outlet sides of 30 the evaporators. The liquid refrigerant within the evaporators 18 and 19 absorbs heat from the air circulating through the duct 10 and is vaporized, the vaporized refrigerant being withdrawn and returned to the condensing units through 35 the suction line 23. The motor 16 is arranged to drive the fan 15 continuously.

The mixture of air passing through the duct 10 may vary widely in temperature and relative humidity, and there is, therefore, a wide variation of the load which must be carried by the evaporators. Since each of the condensing units operates most efficiently within a particular range of loads for which it is designed, it may be desirable to operate only one of the units when the load is relatively small and to operate both units only when full load is required. It will be evident that if the condensing units are designed to carry different loads, it is possible to provide three different ranges of load at which the system may 50 operate efficiently. For example, if the condensing unit 20 is designed to carry a load of 10 H. P. and the condensing unit 21 a load of 20 H. P., it is possible to operate the system with high efficiency at loads of 10 H. P., 20 H. P., and 30 H. P.

In order to operate the cooling system at maximum efficiency, I provide an arrangement for controlling the condensing units and for selecting the units for operation in accordance with the 5 load demand of the system.

In the arrangement shown in Fig. 1, whenever there is a demand for cooling, the thermostat 35 moves to the right and connects a coil 40 across the secondary of a transformer 41, the 10 primary of which is connected across supply lines 42, and a switch 43 is picked up. The upper arm of the switch 43 closes a holding circuit for the coil 40 and the two lower arms connect leads 44 of the motor and control circuit across the lines 42. Motor 32 of condensing unit 20 is thereby connected to be energized 15 through switches 45 and 46 and a line 47. A coil 48 is also connected across the lines 44 through a switch 49. The switches 46 and 49 20 are operated by pressure elements 50 and 52 respectively, which are connected to be responsive to the pressure within the suction line 23. The switches 46 and 49 are pivotally mounted and are operated by the pressure elements 50 and 52 through overcenter springs 46a 25 and 49a respectively; the switch may, therefore, be set to open at a predetermined low pressure and remain open until a predetermined higher pressure has been attained. Such pressure operated switches are commonly employed to control refrigerating machines. The coil 48 is arranged 30 to pick up an armature 53 of a snap operating mechanism 54 for actuating switch 45 to connect the motor 34 across the lines 44 through a lead 55 and the lead 47. It is desirable, however, to prevent the operation of the condensing 35 unit 21 which is driven by the motor 34 if the condensing unit 20 can satisfactorily carry the load of the system and I, therefore, provide a time delay device 56 which may be a dashpot 40 or any other suitable arrangement for delaying the operation of the switch 45 for a predetermined interval of time. If the operation of the condensing unit 20 reduces the pressure within the suction line 23 to a predetermined 45 value, say 25 pounds per square inch, before the mechanism 54 operates to actuate the switch 45, the pressure element 52 will open the switch 49 thereby deenergizing the switch 48 and preventing the actuation of the switch 45. Should 50 the continued operation of the condensing unit 20 reduce the pressure within the suction line 23 to a predetermined minimum, say 20 pounds per square inch, the pressure element 50 will operate to open the switch 46 and stop the motor 55 32. Should the condensing unit 20 fail to reduce the pressure within the suction line 23 sufficiently to open the switch 49, or should the pressure within the suction line 23 rise to a predetermined value, say 30 pounds per square 60 inch, after the switch 49 has been opened initially, the element 52 will close the switch 49. At the end of the interval of time determined by the time delay mechanism 56, the plunger 53 will be fully picked up and will actuate the switch 65 mechanism 54 to snap the switch 45 to its upper position and connect the motor 34 to operate the condensing unit 21. The mechanism 54 as illustrated, comprises a pivoted member 57 connected to the switch 45 by an over-center spring 70 58 to snap the switch between its two extreme positions, it being shown in its lower position. When the armature 53 is fully picked up, a finger 59 engages the member 57 and moves it upwardly so that the overcenter spring snaps the 75 switch to its upper position. When the arma-

ture 53 drops out, a finger 61 engages the member 57 and snaps the switch 45 to its lower position. When the switch 45 is in its upper position, a switch 62 is connected in series in the circuit of the motor 32. The switch 62 is provided with a pressure responsive member 63 and an overcenter spring 62a which are arranged to open the switch 62 whenever the pressure in the conduit 23 falls below some predetermined value, say 30 pounds per square inch. It is, therefore, 10 evident that if the pressure within the conduit 23 is less than 30 pounds per square inch when the condensing unit 21 is connected, the switch 62 will be opened thereby deenergizing the motor 32 and stopping the condensing unit 20. Under 15 this condition of operation, the condensing unit 21 carries the entire load of the system. Should the pressure within the conduit 23 be greater than 30 pounds per square inch when the unit 21 is started, the switch 62 will remain closed. 20 After the switch 62 has been opened by the pressure element 63, the overcenter spring 62a will hold it open until the pressure has risen to, say 35 pounds per square inch. Should the condensing unit 21 be unable to carry the load of 25 the system, the pressure in the line 23 will become sufficiently high to close the switch 62 thereby connecting the motor 32 to drive the condensing unit 21 so that the full capacity of both condensing units is available to carry the 30 load of the cooling system.

Whenever the demand for cooling has been satisfied, the thermostat 35 will move to the left to short-circuit the coil 40 thereby causing the switch 43 to drop out and disconnect the motors 35

During the operation of the cooling system shown in Fig. 1, the motor and control circuits of the condensing units will be energized whenever there is a demand for cooling and the pressure elements 52 and 63 will operate to start and stop the condensing units 20 and 21 in accordance with the load on the system as determined by the pressure of the gaseous refrigerant withdrawn from the evaporators 18 and 19. Operation of the system at maximum efficiency is thereby assured.

Referring again to the drawings, in Fig. 2 I have shown an air cooling system including a duct 64 having a return air inlet 65 and filter 66 and a fresh air inlet 67 and filter 68. Air is 50 circulated continuously through the duct 64 by operation of a fan 69 driven by a motor 70 and the mixture of air is returned to the enclosure or room to be cooled through a duct 71. In order to cool the air passing through the duct 64, I provide two refrigerating machines, one comprising an evaporator 72 and a condensing unit 73 and the other an evaporator 74 and a condensing unit 75. The evaporators 72 and 74 are arranged in the duct 64 so that the air is 55 circulated first over the evaporator 72 and then over the evaporator 74 in series. The condensing unit 73 comprises a compressor 76 driven by a motor 77, a condenser 78 and a liquid receiver 79. The condenser 78 is cooled by water circulated through a casing 80 having an inlet and outlet for the water as indicated by the arrows. Refrigerant is supplied to the evaporator 72 through a liquid line 81 under control of a thermostatic expansion valve 82 having a thermostatic element 83 connected in heat exchange 70 relation to the outlet of the evaporator. Gaseous refrigerant is withdrawn from the evaporator through a suction line 84. The condensing unit 75 is similar to the condensing unit 73 and com- 75

prises a compressor 85 driven by a motor 86, a condenser 87, a liquid receiver 88, and a condenser cooling water casing 89. The liquid and suction lines are indicated at 90 and 91 respectively, and the expansion valve and thermostatic element at 92 and 93.

In order to start and stop the operation of the refrigerating machines to supply refrigerant to the evaporators 72 and 74, I provide a thermostat 94 arranged to be responsive to the temperature of the air in the room to be cooled. When there is a demand for cooling, the thermostat 94 moves to the right and connects a coil 95 across the secondary of a transformer 96, the primary of which is connected across the supply lines 97. This energizes the coil 95 and picks up a switch 98. The upper arm of the switch closes a holding circuit for the coil 95 and the lower arm connects motor and control leads 99 to the supply lines 97 thereby connecting the motors 77 and 86 across the supply lines to start the condensing units 73 and 75. The motor 77 is connected across the lines 99 through a line 100, and switches 101 and 102, and the motor 86 is connected across the lines 99 through the line 100 and a switch 103. The switches 101 and 103 are controlled by pressure responsive members 104 and 105 respectively responsive to the pressures in the suction lines 84 and 91, and arranged to operate the switches through overcenter springs 104a and 105a. These switches comprise the standard type of back pressure control employed on condensing units to stop the operation of the units when a predetermined minimum pressure has been attained.

If the refrigerating machines are of substantially equal capacity, the evaporator 72 will carry about 60 per cent of the load and the evaporator 74 which is operating in cooled air carries about 40 per cent of the load. It is readily apparent that under some conditions of load, one of the evaporators can satisfactorily handle the entire load of the system. It is, therefore, desirable to provide some arrangement for cutting out one of the condensing units in the event the load of the system is sufficiently low to be carried by a single unit. In order to accomplish this purpose, I provide a pressure responsive device 106 having an overcenter spring 106a for opening the switch 102 whenever the pressure within the suction line 91 of the compressor 85 falls below a predetermined value. Opening of the switch 102 opens a circuit of the motor 77 and stops the operation of the condensing unit 73. The entire load then must be carried by the evaporator 74 connected to the condensing unit 75. In order to prevent the immediate reclosing of the switch 102 when the additional load is added to the evaporator 74, the device 106 is arranged to reclose the switch at a pressure substantially higher than that at which it operates to open the switch. The evaporator 74 may, therefore, carry the entire load, and only if the load becomes greater than a predetermined value will the evaporator 72 again be connected for service. Condensing unit 73, therefore, is arranged to be operated in accordance with the load on the condensing unit 75.

Should the demand for cooling be satisfied, the thermostat 94 will engage its left-hand contact and short-circuit the coil 95 thereby causing the switch 98 to drop out and disconnect the motors of the refrigerating machines.

In Fig. 3, I have shown an air cooling system which is similar to that shown in Fig. 2 and cor-

responding parts thereof have been designated by the same numerals. In this arrangement, the condensing unit 73 which supplies refrigerant to the evaporator 72 is started whenever the thermostat 94 calls for cooling and if the load is sufficiently low to be carried by one unit, the condensing unit 75 will not be started. In order to accomplish this result, I provide a switch 107 actuated by a pressure responsive device 108 responsive to the pressure in the suction line 84, an overcenter spring 108a being provided to produce a snap action. When the thermostat calls for cooling and the switch 98 is operated to energize the motor and control circuits and start the motor 77, it also energizes a coil 109 of a switch 110 connected in the circuit of the motor 86. The switch 110 is provided with a time delay device 111 which may be any suitable device for delaying the closing of the switch for a predetermined period after the coil 109 has been energized. In the arrangement illustrated, the device 111 is a dashpot arranged to delay the picking up of the switch 110. If the pressure in the suction line 84 is reduced to a predetermined low value before the switch 110 is closed, the closing of the switch will not start the motor 86 because the device 108 will have operated to open the switch 107. Unnecessary starting of the motor 86 is thereby prevented. Should the condensing unit 73 at any time be unable to carry the load of the system as determined by the suction pressure in the conduit 84, the switch 107 will be closed and the motor 86 will be started to drive the condensing unit 75 and operate the evaporator 74 to cool the air in the duct. Operation of the condensing units 73 and 75 will continue until the demand for cooling is satisfied as determined by the thermostat 94 or until the back pressure in one or both of the suction lines 84 and 91 reaches a predetermined minimum as determined by the pressure responsive elements 104 and 105.

From the foregoing, it is readily apparent that I have provided a simple and effective arrangement for dividing the load of a fluid cooling system between two or more available condensing units and for operating the condensing units at high efficiency.

While I have described my invention in connection with systems for cooling air, other applications will readily be apparent to those skilled in the art, I do not, therefore desire my invention to be limited to the particular constructions shown and described and I intend in the appended claims to cover all modifications within the spirit and scope of my invention.

What I claim as new and desire to secure by Letters Patent of the United States is:

1. A fluid cooling system including a refrigerant evaporator, means including two condensing units for supplying refrigerant to said evaporator and for withdrawing refrigerant from said evaporator, each of said condensing units including means dependent upon a predetermined pressure of refrigerant withdrawn from said evaporator for stopping the operation of said unit, and means dependent upon concurrent operation of said units and responsive to a pressure of said withdrawn refrigerant greater than the predetermined pressure at which the operation of either of said units is stopped by said last-mentioned means for stopping the other of said units.

2. A fluid cooling system including a refrigerant evaporator, means including a plurality of condensing units for supplying refrigerant to

said evaporator and for withdrawing refrigerant from said evaporator, each of said condensing units including means responsive to the suction pressure thereof for stopping the operation thereof at a predetermined low pressure, and means dependent upon a predetermined pressure of the refrigerant withdrawn from said evaporator and independent of said last-mentioned means for stopping the operation of one of said condensing units, all of said stopping means cooperating to determine the sequence of operation of said condensing units.

3. A fluid cooling system including a refrigerant evaporator, means including two condensing units for supplying refrigerant to said evaporator and for withdrawing refrigerant from said evaporator, means dependent upon a demand for cooling for starting one of said units, means dependent upon pressures in excess of a predetermined pressure of the refrigerant withdrawn from said evaporator for starting the other of said units to maintain both of said units in operation, and means dependent upon concurrent operation of said units and responsive to a pressure in excess of said last-mentioned predetermined pressure for stopping the operation of said one of said units.

4. A fluid cooling system including a refrigerant evaporator, means including two condensing units of different full load capacities for supplying refrigerant to said evaporator and for withdrawing refrigerant from said evaporator, means dependent upon a demand for cooling for starting the one of said units having the lower capacity, means dependent upon pressures in excess of a predetermined pressure of the refrigerant withdrawn from said evaporator for starting the one of said units having the higher capacity to maintain both of said units in operation, and means dependent upon operation of said higher capacity unit and responsive to a predetermined pressure of said withdrawn refrigerant in excess of said last-mentioned predetermined pressure for stopping the operation of said lower capacity unit.

5. A fluid cooling system including a refrigerant evaporator, means including two condensing units for supplying refrigerant to said evaporator and for withdrawing refrigerant from said evaporator, means dependent upon a demand for cooling for starting one of said units, means responsive to a predetermined low pressure of said refrigerant withdrawn from said evaporator for stopping said unit, means dependent upon pressures in excess of a predetermined pressure of the refrigerant withdrawn from said units for starting the other of said units to maintain both of said units in operation, means dependent upon operation of both of said units and responsive to a pressure in excess of said last-mentioned predetermined pressure for stopping the operation of said one of said units, and means for delaying the starting of said second unit for a predetermined interval of time after the pressure of said withdrawn refrigerant has reached said predetermined pressure in response to which said other of said units is started.

6. A fluid cooling system including two refrigerating machines, each of said machines having an evaporator, means for circulating a fluid to be

cooled first over one of said evaporators and then over the other of said evaporators, means for controlling said machines, and means dependent upon a predetermined load on one of said machines for stopping the other of said machines. 5

7. A fluid cooling system including two refrigerating machines, each of said machines having an evaporator, means for circulating a fluid to be cooled first over one of said evaporators and then over the other of said evaporators, means 10 for controlling said machines, means for delaying the starting of one of said machines for a predetermined interval of time after operation of said controlling means, and means dependent upon a predetermined load on the other of said machines for stopping said one of said machines.

8. A fluid cooling system including two refrigerating machines, each of said machines comprising a compressor and a condenser and an evaporator, each of said machines including a 20 pressure operated device for stopping the operation of the compressor thereof, means for circulating a fluid to be cooled over said evaporators in series, means for controlling the operation of said machines, and means responsive to a predetermined pressure of the refrigerant on the suction side of one of said compressors for stopping the operation of the other of said compressors. 25

9. A fluid cooling system including two refrigerating machines, each of said machines comprising a compressor and a condenser and an evaporator, means for circulating a fluid to be cooled over one of said evaporators and then over the other of said evaporators, means for controlling said machines to supply refrigerant to and withdraw refrigerant from said evaporators, and means responsive to a predetermined pressure of the refrigerant withdrawn from said other of said evaporators for stopping the supply of refrigerant to said one of said evaporators. 40

10. A fluid cooling system including two refrigerating machines, each of said machines comprising a compressor and a condenser and an evaporator, means for circulating a fluid to be cooled over one of said evaporators and then over the other of said evaporators, means for controlling said machines to supply refrigerant to and withdraw refrigerant from said evaporators, and means responsive to a predetermined pressure of the refrigerant withdrawn from said one 45 of said evaporators for stopping the supply of refrigerant to said other of said evaporators. 50

11. A fluid cooling system including two refrigerating machines, each of said machines comprising a compressor and a condenser and an 55 evaporator, means for circulating a fluid to be cooled over one of said evaporators and then over the other of said evaporators, means for controlling said machines, means for preventing the starting of said refrigerating machine including 60 said one evaporator for a predetermined interval of time after the starting of said other refrigerating machine by operation of said controlling means, and means responsive to a predetermined pressure of the refrigerant withdrawn 65 from said other of said evaporators for stopping the supply of refrigerant to said one of said evaporators.

HARRY R. CRAGO.
